Nissen Crane

UNITED STATES PATENT OFFICE

CORNELIS F. M. VAN BERKEL, OF WASSENAAR, NETHERLANDS, ASSIGNOR TO U. S. SLICING MACHINE COMPANY, OF LA PORTE, INDIANA, A CORPORATION OF INDIANA

SLICE STACKER FOR SLICING MACHINES

Application filed September 6, 1928, Serial No. 304,232, and in The Netherlands September 19, 1927.

The present invention relates to mechanism for slicing meat and other commodities and for stacking the slices on a receiving tray or table. The conveyer mechanism includes, as usual, two chains spaced above one another as shown in my prior patents No. 1,290,425 and No. 1,573,953, which patents also disclose in detail the mode of operation of this type of slicing machine. In my prior patent No. 1,674,381, patented June 19, 1928, I have disclosed a conveyer mechanism in which metal bands are used instead of the usual chains. In the present application, I have provided a novel means for detachably holding the ends of the metal bands together so that the bands with their attached members for engaging the material sliced can be easily removed from the machine.

The detachable holding means for converting the steel band into an endless conveyer band is pivoted to one of the pin carrying members positioned adjacent to one end of the band and is detachably connected to a pin carrying member positioned adjacent to the other end of the band. The relation of the parts is such that the distance between the points connecting the detachable holding means remains uniform at all positions of the strip, the distance between these points being the same as that between the successive pin carrying members.

In the drawing:

Fig. 1 is a front elevation of a slice carrying device showing its relation with a slicing machine;

Fig. 2 is a top plan view of the slicing machine showing the slice carrying mechanism in section as indicated by the line II-II in Fig. 1; and

Fig. 3 is a perspective view illustrating the detachable connection between the ends of the upper and lower steel bands.

The numeral 1 denotes the base of a slicing machine having a rotary slicing knife 2 and a reciprocating carriage 3 slidable on the rods 5 and 6. The hand wheel 4 drives mechanism well known in the art for rotating the knife and reciprocating the table. A supporting plate or bracket 25 is secured to the front edge 50 of the base 1 and carries the conveying mech-

anism by means of which the slices are transferred from the material as they are sliced and brought to a position where they may be discharged onto the receiving tray or support, as more fully described in my previously referred to patents.

Carried by the plate 25 and spaced upwardly therefrom by spacing bolts 8 and bearing sleeves 41 is a guide plate 40 having a peripheral flange 7 thereon. Spaced inwardly from the flange 7 is a second flange 18 held in spaced relation with the flange 7 by angle irons 19. The flanges 7 and 18 provide a guide slot for receiving a metal band or tape 20, preferably of steel. The band 20 projects upwardly above the top edge of the flanges 7 and 18 as shown in Fig. 1.

Spaced upwardly from the plate 40 and supported thereon by spacing bolts 9 and 10 is a second guide plate 41 having a peripheral flange 7' and an inner flange 18' held in spaced relation with the flange 7 by angle brackets 19 in a manner similar to the flanges on the lower guide plate 40. A band 21 similar to the band 20 is guided between the flanges 7' and 18' and projects downwardly below the lower edges of the flanges. The two metal bands are connected by a series of spaced upright bars 22 which are riveted or otherwise attached at 24 to the inner faces of the projecting portions of the bands as best shown in Fig. 3. The members 22 have portions 42 which space the bars 22 inwardly from the bands 20 and 21 to permit the ends of the pins 23 carried by the bars 22 to be in substantial alignment with the bands 20 and 21.

The metal bands 20 and 21 are driven by discs 27 and 28 secured to a shaft 11, the lower end of which is journaled in the bearing 41 on the plate 25 and the upper end of which is journaled in a bearing 12 on the plate 41. The discs 27 and 28 are provided with notches 41' which engage the ends 45 of the bars 22 to positively drive the bands with their attached bars 22.

The lower end of the shaft 11 is provided with a gear 14 which meshes with a pinion 17 carried on a stud shaft 46, the upper end of which is provided with a pinion 16 which 100

meshes with a rack 15 on the reciprocating table 3. The particular form of driving connection between the discs and the bands is not material as several modes of effecting the 5 desired result will occur to those skilled in the art. The bands could be provided with special ribs for the notches 41' or the discs might be provided with pins to engage holes in the bands.

10 The bands 20 and 21 abut with their ends against each other, as shown at 29 in Fig. 3. A metal strip 30 is pivoted by a pin 31 on the horizontal portion 42 of the bar 22 that is attached on one end of the band 20 adjacent the 15 end of the band. The other end of the strip 30 has a hook portion 32 which engages a pin 33 on the horizontal portion 42 of the bar 22 attached adjacent the other end of the band 20. The axis of the pins 31 and 33 are each 20 located in a straight line lying in that vertical plane which projects through the points of the pins 23. These pins therefore remain at a uniform distance during movement of the machine and because the distance of the 25 pins 31 and 33 is equal to the distance between the points of the pins 23, the mutilation or tearing of the meat or other substance sliced is prevented.

It will be noted that the horizontal portions 42 of the bars 22 have extended portions 43 which project slightly beyond the band 20. This additional ledge portion 43 facilitates the placing of the pins in line with the band 20 and ends of pins 23.

25 The flanges 7 and 7' are provided with removable end portions which are releasably held in place to close the ends of the guide slots for the steel bands. The steel bands 20 and 21 with the connecting bars 22 can be 40 easily and quickly removed from the guides by removing the detachable sections 26 and then removing the hooked end of the strip 30 from the pin 32. By reason of this construction, the separate parts of the conveyer may 45 be readily inspected and cleaned.

I claim:

1. Conveyer mechanism for slicing machines comprising in combination a flexible metal band the ends of which are positioned 50 in abutting relation to each other to form a substantially endless conveyer band, slice carrying members attached to said band, impaling pins on said members, said members having a portion thereof spaced inwardly from said band to position the points of said pins in substantial alignment with said band, and a latching member the ends of which directly connect slice carrying members attached to opposite ends of said band and hold the ends 55 of said band in abutting relation.

2. Conveyer mechanism for slicing machines comprising in combination a flexible metal band the ends of which are positioned adjacent to each other to form a substantially 60 endless conveyer band, slice carrying mem-

bers attached to said band, impaling pins on said members, said members having a portion thereof spaced inwardly from said band to position the points of said pins in substantial alignment with said band, and a latch member 70 detachably connecting the ends of said band, the points of connection of said latch member with said band being in substantial alignment with the edge of said band and with the points of said pins.

3. Conveyer mechanism for slicing machines comprising in combination a flexible metal band the ends of which are positioned adjacent to each other to form a substantially 75 endless conveyer band, slice carrying members attached to said band, impaling pins on said members, said members having a portion thereof spaced inwardly from said band to position the points of said pins in substantial alignment with said band, and a latch member 80 pivotally carried by said band adjacent one end of said band, said latch having means thereon for detachable connection with the other end of said band, the points of connection of said latch member with said band 85 being in substantial alignment with the edge of said band and with the points of said impaling pins.

4. Conveyer mechanism for slicing machines comprising in combination, a flexible metal band, the ends of which are positioned adjacent to each other to form a substantially 90 endless conveyer band, slice carrying members attached to said band, impaling pins on said members, one of said members being attached to said band adjacent one end thereof, another of said members being attached to said band adjacent the other end thereof, said members each having an inwardly extending attaching portion for spacing the 95 slice carrying portion of said members inwardly from said band to position the points of said pins in substantial alignment with the edge of said band, and a latch member 100 detachably connecting said slice carrying members positioned on opposite ends of said band, the points of connection of said latch member with said slice carrying members being in substantial alignment with the edge 105 of said band and with the points of said pins.

5. Conveyer mechanism for slicing machines comprising in combination, a flexible metal band, the ends of which are positioned adjacent to each other to form a substantially 110 endless conveyer band, slice carrying members attached to said band, impaling pins on said members, one of said members being attached to said band adjacent one end thereof, another of said members being attached to said band adjacent the other end thereof, 115 said members having an inwardly extending attaching portion for spacing the slice carrying portion of said members inwardly from said band to position the points of said pins in substantial alignment with the edge of 120

said band, and a latch pin carried by the inwardly extending portions of said members positioned adjacent opposite ends of said bands, the axes of said pins being in substantial alignment with the edge of said band and with the points of said impaling pins, a latch member pivoted on one of said latch pins, said latch member having a hooked portion thereon for detachably engaging the other of said latch pins.

6. Conveyer mechanism comprising in combination an upper guide, a lower guide, a flexible metal band in each of said guides, the ends of said bands being positioned adjacent to each other to form a substantially endless conveyer band, slice carrying members connecting said bands, impaling pins on said members, said members having an inwardly extending attaching portion to space the slice carrying portions of said members inwardly from said band and to position the points of said impaling pins in substantial alignment with the edges of said bands, and a latch member connecting the adjacent ends of one of said bands, the points of connection of said latch member with said band being in substantial alignment with the edges of said bands and with the points of said pins.

7. Conveyer mechanism comprising in combination an upper guide, a lower guide, a flexible metal band in each of said guides, the ends of said bands being positioned adjacent to each other to form a substantially endless conveyer band, slice carrying members connecting said bands, impaling pins on said members, said members having an inwardly extending attaching portion to space the slice carrying portions of said members inwardly from said band and to position the points of said impaling pins in substantial alignment with the edges of said bands, a latch pin carried by each of the adjacent ends of said band, the axes of said pins being in substantial alignment with the edges of said bands and with the points of said impaling pins, and a latch pivoted on one of said pins, said latch having a hook portion for detachably engaging the other of said pins.

8. Conveyer mechanism comprising in combination an upper guide, a lower guide, a flexible metal band in each of said guides, the ends of said bands being positioned adjacent to each other to form a substantially endless conveyer band, slice carrying members connecting said bands, impaling pins on said members, said members having an inwardly extending attaching portion to space the slice carrying portions of said members inwardly from said band and to position the points of said impaling pins in substantial alignment with the edges of said bands, and a latch member detachably connecting the inwardly extending attaching portions of slice carrying members positioned adjacent opposite ends of one of said bands, the points of con-

nnection of said latch member with inwardly extending portions being in substantial alignment with the edges of said bands and with the points of said impaling pins.

9. A slicing machine comprising an endless slice conveyer having a flexible metal band trained about a plurality of rotatable elements, a plurality of conveying elements secured to said band, a latch secured to one side of said flexible band adjacent the end thereof and adapted to engage a latch member on the opposite adjacent end of said flexible band to hold the ends of said band detachably in predetermined relation with each other, said latch member being located on the edge of said band which does not change its plane of movement as it passes over said rotatable element thereby preventing said latch member from interfering in any substantial way with the movement of said flexible band about said rotatable element.

10. A device as claimed in claim 17 in which one of said rotatable elements has means thereon adapted to engage portions of said conveying elements to positively drive said band, said latching means being so constructed as to hold the ends of the band in proper relation to each other so that the conveying elements adjacent each end of said band may be in proper spaced relation to each other so that the same will be properly engaged by the means on said rotatable element as the conveying elements and the rotatable driving element come into engagement with each other.

In testimony whereof I have signed my name to this specification on this 17th day of August A. D. 1928.
